ATTORNEYS

UNITED STATES PATENT OFFICE.

WINSOR JOSSELYN, OF CARMEL, CALIFORNIA.

CIGARETTE HOLDER.

Application filed November 26, 1919. Serial No. 340,759.

To all whom it may concern:

Be it known that I, WINSOR JOSSELYN, a citizen of the United States, and a resident of Carmel, in the county of Monterey and State of California, have invented a new and Improved Cigarette Holder, of which the following is a full, clear, and exact description.

This invention relates to cigarette and 10 cigar holders and more particularly to a cigarette or cigar stub ejector device used in connection with cigarette and cigar mouthpieces.

An object of the invention is to provide a 15 cigar or cigarette stub or butt ejector device which may be inserted in the mouthpiece of the holder for forcibly removing the cigarette or cigar stub from the mouthpiece without the necessity of the smoker using his 20 knife or other implement for gouging and removing the stub end of the burned cigar or cigarette from the holder. It is also an object to provide an ejector device which acts to clean the opening or channel through the 25 cigar or cigarette holder at the time it is operated to eject the stub.

It is a further object to provide a smokers' accessory of the character described which is comparatively inexpensive 30 to produce, simple to manufacture, ornamental in nature, and which positively functions to perform the aforesaid purposes.

With the above principal objects and advantages in view, the invention has relation 35 to the ejector device as described in the following specification, set forth in the appended claims, and illustrated in the accompanying drawings, wherein:

Figure 1 shows a perspective view of a 40 cigar or cigarette mouthpiece with the ejector mounted therein, and Figure 2 shows a sectional view thereof.

The Figures 3, 4 and 5 disclose the three 45 major views of the ejector device removed from the mouthpiece.

Referring now more particularly to the drawings, a cigar or cigarette holder of conventional and ordinary design as is in daily use is designated by the reference character 50 7. This holder is constructed of any suitable material provided with a smoke channel 8 drilled through the stem 7 and with an enlarged bore 9 formed in one end of the holder. The cigar or cigarette is thrust into 55 the bore 9 and frictionally held during the smoking period.

It is the purpose of this invention to provide a device which acts to positively remove the stub or unsmoked end from the bore 9 and with this in view the ejector device constructed in accordance with my invention comprises an ejector with a hook on one end placed within the holder to forcibly remove the stub displaced by the finger of the smoker. A more detailed description of the ejector shows a spring arm 12 provided on one end with a scraper 14 and on the other end with a hook 15. A stop 16 is made on the ejector between the hook 15 and spring arm 12. The stop 16 is made by bending the spring arm 12 to form an incline or an abutment adjacent the hook 15 in order that the cigar or cigarette may not be thrust by the stop 16 when inserted in the holder.

The ejector device is inserted in the holder 7 as shown in Figure 2 by thrusting the scraper end 14 into the smoke channel 8. This compresses the spring arm 12 causing the device to flatten out through the smoke channel and the hook 15 engages the rim of the holder and properly positions the stop 16 within the bore 9. The stop 16 therefore blocks the bore 9 against excessive inward movement of a cigarette within the holder. 80 The stop 16 is so arranged as to adequately admit of the insertion of a cigarette to retain it within the holder but will prevent the cigarette from being thrust too far into the bore 9 as to prevent the burned end from being ejected by the smoker.

In use, the finger or thumb of the smoker will grasp the hook 15 and move it outwardly, at which time the burned end of the cigarette or cigar is forcibly ejected from the bore 95 9 by the action of the stop 16 moving against the unburned end or stub. At the same time the scraper 14 acts to scrape and clean the channel 8 of burned residue or injurious matter which may collect in the channel 8 100 incident to the combustion of tobacco. The device is therefore capable of cleaning out the holder simultaneously with the ejection of the burned stub.

The ejector is constructed of any suitable 105 material, preferably spring brass, spring copper, spring nickel, or any non-corrosive, metallic material having sufficient resiliency to enable it to conform to the bore of the mouthpiece when thrust into position. It is 110 simple in design, formed of one-piece material, and incapable of getting out of work-

ing order. The design, shape and size of the spring arm 12 is such that the passage of the smoke through the channel 8 will not be impeded. The use of the device renders it unnecessary for the smoker to use his fingers or other means for removing burned stubs from the holder. The combination ejector and cleaner will likewise be adapted for use in connection with pipe stems for 10 cleaning out the burned residue which frequently collects in the stem of a pipe. The invention is presented to fulfill the needs felt for a smokers' utility device of the character described.

Having thus described my invention, what I claim as new and desire to secure by Letters Patent is:

1. The combination with a cigar or cigarette holder having a longitudinal bore therethrough of a butt ejector mounted within said bore, said ejector being provided with a scraping element engaging the walls of the bore and functioning to clean the same when the ejector is operated.
2. A cigar and cigarette holder comprising in combination, a mouthpiece having an enlarged bore and a reduced smoke channel, an ejector device inserted in the mouthpiece, a scraper made on the ejector for cleaning the smoke channel, and a hook formed on the ejector.
3. An ejector for use in connection with cigar and cigarette holders comprising, a flexible spring, a hook made on one end of the flexible spring, and a scraper made on the other end thereof such that the device will eject the burned stub from the holder and simultaneously clean the holder.
4. An ejector device for use in connection with cigarette and cigar holders comprising, a flexible metallic spring arm, a stop made

on the arm, a hook made adjacent the stop, and a scraper made on the other end of the arm.

5. A combination ejector and cleaner for 45 use in connection with cigar and cigarette holders where the holder is provided with an enlarged bore for receiving the end of the cigar or cigarette, and is further provided with a reduced smoke channel, said ejector and cleaner comprising, a flexible spring piece, a hook made on one end thereof for engaging the rim of the enlarged bore of the holder, a scraper made on the other end thereof to project into the reduced bore, 50 and a stop formed adjacent the hook to thrust a cigar or cigarette end from the enlarged bore.

6. The combination with a cigar or cigarette holder having a longitudinal bore therethrough of a butt ejector mounted therein and being capable of reciprocatory motion with respect thereto, and a resilient scraper element carried by said ejector, said scraper 55 engaging the walls of the bore to frictionally retain the ejector in any one of a plurality of predetermined positions and to clean the walls of said bore when the ejector is operated.

7. The combination with a cigar or cigarette holder having a longitudinal bore therethrough of a butt ejector mounted with in said bore, means carried by said ejector and lying without said holder to reciprocate 75 said ejector within the bore, and a scraper carried by said ejector to frictionally engage the walls of the bore and functioning to simultaneously retain the ejector in any one of a plurality of predetermined positions and to frictionally cleanse said walls 80 when the ejector is reciprocated.

WINSOR JOSSELYN.
